UNITED STATES PATENT OFFICE.

LE ROY W. FAIRCHILD, OF NEW YORK, N. Y.

DESIGN FOR PENCIL-CASES.

Specification forming part of Design No. **11,415**, dated September 16, 1879; application filed August 7, 1879.
[Term of patent 7 years.]

To all whom it may concern:

Be it known that I, LE ROY W. FAIRCHILD, of the city, county, and State of New York, have produced a new and original Design for Cases for Pencils and other small implements, to be worn as an amulet upon watch-chains, or otherwise, of which the following is a full, clear, and exact description, reference being had to the accompanying engraved illustration, making part of this specification.

A represents the design as a whole. b is the tail of the lizard, so arranged as to form an eye or loop. c is an ornamental bead at the junction of the greater and lesser tubes of the case. d d d d are the four limbs of the lizard, so arranged that the segregated mem-

bers terminating in claws are brought in close contact with the body to insure smoothness, as shown at e e e e. f is the head, with mouth distended.

The implement incased is not shown, as it forms no part of the design.

What I claim as my invention is—

A design for a small implement-case, A, being in the form of a lizard, with looped tail b, bead c, limbs d d d d, claws e e e e, and head f, substantially as above described.

LE ROY W. FAIRCHILD.
